UNITED STATES PATENT OFFICE.

EDWARD A. FRIESE, OF BIRMINGHAM, ALABAMA.

SYRUP-PUMP.

1,045,964.

Specification of Letters Patent.

Patented Dec. 3, 1912.

Application filed February 11, 1911. Serial No. 608,010.

To all whom it may concern:

Be it known that I, EDWARD A. FRIESE, a citizen of the United States, residing at Birmingham, in the county of Jefferson and State of Alabama, have invented new and useful Improvements in Syrup-Pumps, of which the following is a specification.

This invention relates to improvements in pumping apparatus for fluids, and while it can be as readily employed with any kind of a fluid, yet it is of particular advantage in pumping syrups from syrup jars in soda fountains.

The objects of this invention are to construct an apparatus for discharging the contents of a fluid receptacle which fluid will be positively discharged from the bottom of the receptacle, to provide means to keep the discharge pipe filled at all times, and to provide a drain for the discharge nozzle which will return the fluid either to the interior of the receptacle or to the bottom of the fluid contained therein.

It is also an object of this invention to include a stroke regulating device for operating the discharge mechanism, and also to provide a series of interlocking covers when the invention is employed in connection with soda fountains which will prevent any of the waste water or other foreign substances from entering into the syrup containing jars.

The advantages of this invention when applied to syrup jars of soda fountains are obvious. The syrup being taken from the bottom of the jar at each discharge it dispenses the oldest, coldest, heaviest, thicker syrup first, thereby rendering it impossible for the syrup to crystallize. As the measuring chamber is filled from the bottom every downward stroke of the piston will discharge all of the syrup therefrom. As the discharge pipe is provided with a check valve at the bottom, the pipe will always be filled with syrup up to the top of the jar regardless of the amount of syrup in the jar, and therefore the same amount of syrup will be actually dispensed at each operation. A return pipe leading from the nozzle to the bottom of the measuring chamber upon the upward stroke of the piston will draw back into the measuring chamber all of the syrup in the discharge nozzle and thereby prevent dripping at the discharge end. As the jar covers interlock no water, dirt or other foreign matter can enter the syrup receptacles.

The piston stroke regulating device is so constructed that no foreign matter can enter within the receptacle through the sleeve surrounding the piston rod where it passes through the cover.

While the preferred forms of this invention are illustrated upon the accompanying sheet of drawing, yet it is to be understood that minor detail changes may be made without departing from the scope thereof.

Figure 1 is a view in vertical section taken through one form of this invention as applied to a soda water fountain. Fig. 2 is an enlarged front view partly in section of a modified form of the invention illustrating the discharge and return pipes, and discharge end of nozzle with parts broken away. Fig. 3 is a view in perspective illustrating the interlocking of the covers with the front flange broken away.

The drawings illustrate this invention as applied to a syrup receptacle in a soda fountain in which there is a space between the dispensing slab 1 and the vertical partition 2 for the insertion and removal of the syrup receptacle 3. A cover 5 is supported over the jar 3 by engaging portions of the slab 1 and vertical partition 2 and this cover 5 supports the pumping mechanism.

While it is preferable to form the syrup receptacle with a depressed portion adapted to receive the measuring chamber as illustrated, yet it is not essential to this invention. The measuring chamber 6 is provided with a discharge pipe 7 leading from the front thereof to the nozzle 8, which is preferably screw threaded to the cover 5. The bottom of the measuring chamber is supported by legs 9 above the bottom of the syrup receptacle 3, and is provided with a depression 10, which rests upon the bottom of the receptacle 3 and this depression is in communication with the bottom of the measuring chamber 6 and the bottom of the discharge pipe 7, so that the liquid in the measuring chamber will pass therefrom into the bottom of the discharge pipe 7. A check valve is provided preferably at the bottom of the discharge pipe 7 which will allow the fluid to pass therethrough but not return. This check valve 12 is preferably of the ball and socket type. A flap valve 13 is preferably mounted at the top of the discharge pipe 7 allowing the fluid to pass therethrough into the discharge nozzle and arranged in an inclined position when closed.

to direct the returning syrup at the end of the discharge into a return pipe 14 leading to the interior of the receptacle 3. While the fluid is being discharged the flap valve 13 will close the opening into the return pipe 14 and thereby positively dispense the contents of the measuring chamber at each operation of the piston. The spring 13^a will positively return the valve 13 to the inclined position over the discharge pipe 7 after each operation. The bottom of the measuring chamber 6 is provided with an intake valve 16 upon the bottom and this valve 16 is adapted to be received in a recessed portion, so that the piston 17 may come flush with the bottom of the measuring chamber. On the under side of the intake valve a strainer 18 is provided which may be a perforated plate or a wire mesh, and will prevent foreign substances from being dispensed with the syrup.

A piston rod 19 is provided with an adjustable stroke limiting device, which will enable the operator to dispense a given quantity of syrup at each operation. This stroke limiting device comprises a tubular member 20, preferably screw threaded to the upper end of the piston rod 19. A sleeve 21 is secured to the cover 5 and through this sleeve the tubular member 20 passes. The tubular member 20 is provided at the exterior end with a cap 22 upon which may be displayed a syrup label 23. A cap sleeve 24 depends from the under side of the cap 22 and is preferably screw threaded thereto, said sleeve being of sufficient diameter to pass snugly over the cover sleeve 31, and these sleeves 31 and 24 are of such lengths that upon the utmost downward stroke of the piston rod 19, the bottom of the cap sleeve 24 will engage the plate 25 secured to the cover 5, and yet upon the end of the upward stroke the bottom of sleeve 24 will overlap the top of sleeve 21. Sleeve 24 is provided with an adjustable ring 26 which is preferably screw threaded on the interior and in engagement with a similarly screw threaded portion upon the bottom of the cap sleeve 24. The top of the ring 26 is preferably provided with an internal flange adapted to engage with an external flange upon a retaining ring 27, which is provided with a set screw adapted to engage the cap sleeve 24 and retain the retaining ring in position thereon. The piston is retained at the uppermost end of its stroke by a spring 28 upon the interior of the tubular member 20 which spring is in engagement with the under side of the cap 22 or syrup label carried thereby and is provided with a securing means at the bottom. The sides of the tubular member 20 are provided with slots diametrically opposite each other and a pin or bolt 29 is passed through these slots and in engagement with depending members upon

the cover 5. The pin 29 engages the bottom of the spring and holds it in position.

By loosening the set screw upon the retaining ring 27, the ring 26 may be adjusted upon the cap sleeve to the position required and upon screwing up the set screw on the retaining ring 27 it will be retained in this position, so that upon the downward stroke of the piston the lower portion of the ring 26 will engage the plate 25 and determine the amount of syrup at each discharge. 75

Syrup jars are usually arranged side by side in soda fountains, and in accordance with this invention the cover 5 is provided with means interlocking with the adjacent covers and with means interlocking with a portion of the slab 1 and vertical partition 2 to prevent any foreign substance entering between the covers or between the cover and supporting means and gaining access to the interior of the syrup receptacles. To this end each cover is provided with four depending flanges. The depending flange 30 on one side is perfectly straight. The depending flange 31 on the other side is bent back upon itself, as clearly shown in Fig. 3, so that it will engage and interlock with the straight flange 30 upon the adjacent cover. It is preferable that an angle iron 32 be secured to the underside of the dispensing slab 1 to support the covers 5 and the angle in this iron extends a sufficient distance beyond the slab 1 to allow the rear flange 33 to engage thereon. The side flanges 30 and 31 are cut away at 34 to allow for this angle 32. The side flanges 30 and 31 are terminated short of the front edge of the cover 5 and fit snugly against the inner side of the top of the vertical partition 2. A depending flange or rib 35 projects downward from the front of the cover 5 and the vertical partition 2 is provided with a depression or groove to receive the flange 35. The back of the cover 5 may be supported in the same manner upon the slab 1, if desired, without altering the construction of the back flange. 105

In Fig. 2 another form is disclosed. In this form a return pipe 13^a is shown leading from the nozzle 8 to the bottom of the dispensing chamber 6. This return pipe 13^a is provided with a check valve 36 at the bottom thereof which will prevent the discharge of syrup therethrough from the measuring chamber upon the descent of the piston. The upper end of the discharge pipe 7 is provided with a flap valve 37 allowing a discharge of the syrup therethrough and is so weighted that it will close in an inclined position which will direct the returning syrup to the return pipe 13^a. The end of the discharge nozzle, as shown in the broken away portions of Fig. 2, is provided with a perforated closure 38 through which the syrup may be discharged, but which will 130

prevent ants or other insects crawling into the discharge nozzle.

The sleeve 21 is preferably graduated upon the outside in order that the exact amount of fluid discharged with each operation may be determined and adjusted.

A plug 40 is preferably provided below the bottom of the discharge pipe to allow of cleaning the same, and the check valve at 10 the bottom of the pipe may be removable with the plug if desired. When the discharge pipe and return pipe both communicate with the measuring chamber as shown in Fig. 2, a removable plug may be placed 15 beneath each one and both check valves may be removable with these plugs if desired.

On the underside of the cover 5 between the flanges thereof a piece of cork or other insulation 41 may be placed. As the syrup 20 in the jar is kept at a low temperature by a refrigerant generally within the counter and as the top of the jars are usually of metal, an insulation upon the jar top will prevent transmission of heat from the atmosphere 25 through the top to the contents of the jar.

What I claim is:

1. In a pumping apparatus, a fluid receptacle and means for discharging the contents thereof including a measuring chamber and 30 a discharge nozzle, a discharge pipe leading from the measuring chamber to the nozzle, a valve in said pipe preventing the return of the fluid therethrough, a return pipe leading from the nozzle to the chamber, and a valve 35 therein preventing a discharge of the fluid therethrough.

2. In a pumping apparatus, a fluid receptacle and means for discharging the contents thereof including a measuring chamber supported above the bottom of the receptacle, 40 an intake valve in the bottom of the chamber, a discharge nozzle, a discharge pipe leading from the bottom of the chamber to

the nozzle, and a return pipe leading from the nozzle to the bottom of the measuring 45 chamber.

3. In a pumping apparatus, a fluid receptacle and means for discharging the contents thereof including a measuring chamber supported above the bottom of the receptacle, 50 an intake valve in the bottom of the chamber, a discharge nozzle, a discharge pipe leading from the bottom of the chamber to the nozzle, a valve therein preventing a return of the fluid therethrough, and a return 55 pipe leading from the nozzle to the bottom of the measuring chamber.

4. In a pumping apparatus, a fluid receptacle and means for discharging the contents thereof including a measuring chamber supported above the bottom of the receptacle, 60 an intake valve in the bottom of said chamber, a discharge nozzle, a discharge pipe leading from the bottom of the chamber to the nozzle, a valve therein preventing a return of the fluid therethrough, a return pipe leading from the nozzle to the bottom of the 65 chamber, and a valve therein preventing a discharge of the fluid therethrough.

5. In a pumping apparatus, a fluid receptacle and means for discharging the contents thereof including a measuring chamber and a discharge nozzle, a discharge pipe leading from the chamber to the nozzle, a valve at 75 the lower end of the discharge pipe preventing the return of the fluid therethrough, a return pipe leading from the nozzle to the chamber, a valve at the lower end of the return pipe preventing a discharge therethrough, and a valve in the discharge pipe 80 in proximity to the nozzle directing the returning fluid into the return pipe.
